UNITED STATES PATENT OFFICE

162,542

COMBINED TABLE AND STORAGE UNIT

Eda A. Hurwitz, Marblehead, Mass.

Application July 25, 1947, Serial No. 140,514

Term of patent 14 years

(Cl. D33—19)

To all whom it may concern:

Be it known that I, Eda A. Hurwitz, a citizen of the United States, residing at Marblehead, in the county of Essex and Commonwealth of Massachusetts, have invented a new, original, and ornamental Design for a Combined Table and Storage Unit, of which the following is a specification, reference being had to the accompanying drawing, forming part thereof.

Fig. 1 is a perspective view of a combined table and storage unit, showing my new design as viewed from the front.

Fig. 2 is a top plan view thereof.

Fig. 3 is an elevational view of the side opposite to that shown in Fig. 1, and

Fig. 4 is a view of the opposite end of my combined table and storage unit.

The drawing figures have been shaded to show contrasting appearance.

I claim:

The ornamental design for a combined table and storage unit, substantially as shown and described.

EDA A. HURWITZ.
